UNITED STATES PATENT OFFICE.

FRANKLIN L. DOWNEND, OF HALIFAX, NOVA SCOTIA, CANADA, ASSIGNOR
TO CHARLES FRANKLIN MOTT, OF SAME PLACE.

COMBINATION-TOOL.

SPECIFICATION forming part of Letters Patent No. 426,409, dated April 22, 1890.

Application filed November 25, 1889. Serial No. 331,413. (No model.) Patented in Canada August 1, 1889, No. 31,851.

To all whom it may concern:

Be it known that I, FRANKLIN L. DOWNEND, of Halifax, in the county of Halifax, in the Province of Nova Scotia, in the Dominion 5 of Canada, have invented certain new and useful Improvements in Combination-Tools, (for which I have received a patent of the Dominion of Canada, No. 31,851, dated August 1, 1889;) and I do hereby declare that 10 the following is a full, clear, and exact description of the same, reference being had to the accompanying drawings, in which—

Figure 1 is a front elevation of my improved implement. Fig. 2 is a side view of the same, 15 and Fig. 3 is a side view of the cutter detached.

My invention has for its object to combine in an implement, presumably a hammer or hatchet, a claw for extracting nails and tacks, 20 a corkscrew, and a cutter for opening cans, &c., and my device may be used for many other useful purposes.

My invention consists in combining with a hammer or hatchet having a skeleton handle 25 cast integrally therewith an adjustable cutter sliding in the upper part of the handle, a corkscrew in the lower part of the handle, the handle terminating in a claw, and the head of the hammer or hatchet provided with 30 a spike for centering the cutter, as hereinafter set forth.

A is the hammer-head, or hatchet, if desired, and B is a skeleton handle cast integral with the head, and said handle is cast with a 35 solid partition C near the middle. The upper division of the handle is occupied by a cutter D, pivoted between opposite sides of the handle by a bolt J, passing through the cutter-head and through the opening in the side of 40 the handle and extending therefrom, the extended end of the bolt provided with a thumb-nut E, screwing thereon, to clamp the cutter to the side of the handle, so that when the nut is loosened the cutter will fold within the

skeleton handle, as shown in dotted lines in 45 Fig. 2, and be removed, whereby the point will be protected from injury.

One end of the hammer-head is provided with a spike F, and in opening a can the spike is inserted through the end of the can 50 at the center and the cutter worked around the can at the line where cutting is to be effected. The lower end of the handle is grasped by the hand in effecting the cut.

The cutter when adjusted to the line of cut 55 is fixed by the thumb-screw clamping the cutter between the open bars of the handle, and when cutting is to be effected the blade D is projected outwardly from the handle, and when cutting has been performed the cutter 60 is folded to shut the point of the blade between the bars of the handle.

G is a corkscrew located in the lower division of the handle, and preferably it is pivoted between springs H H, which are secured in 65 the open handle by screws or rivets I. These springs serve to retain the corkscrew closed, and are suitably notched at the free end for that purpose.

The lower end of the handle terminates in 70 a claw K, for prying out driven tacks and nails, opening boxes, and for other useful purposes.

I claim as my invention—

The combination, with the skeleton handle 75 B, subdivided by a partition C and having a head A, provided with a spike F, of the cutter D, adjustable between the open sides of the handle, a headed bolt J, passing through said sides and cutter, and a thumb-nut E, 80 screwing on the bolt and against the handle, whereby the cutter folds in and is clamped to the handle, as set forth.

FRANKLIN L. DOWNEND.
